SHADE HANGER

William M. Banks, Erie, Pa.

Application January 16, 1940, Serial No. 314,152

3 Claims. (Cl. 248—266)

The invention relates to a window shade fixture and more especially to a shade hanger for fitting a window or the like.

The primary object of the invention is the provision of a hanger of this character wherein through the use of a plurality of sections the hanger is susceptible of reasonable adjustment and these sections are interfitted and fastened together, the main or intermediate section being of a construction for the engagement of the outer or other sections therein and in a manner to give maximum strength to the said outer sections to withstand the weight and usage of the shade roller when a window shade is supported in the hanger.

Another object of the invention is the provision of a hanger of this character wherein a shade roller can be fitted therein and held supported with relation to a window frame, the hanger being adjustable for the fitting thereof to various widths of window frames.

A further object of the invention is the provision of a hanger of this character wherein its parts are made from metal, assuring strength and rigidity so as to withstand severe usage and the proper supporting of a window shade.

A still further object of the invention is the provision of a hanger of this character, which is extremely simple in its construction, being possessed of few parts, strong, durable and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a perspective view of the hanger constructed in accordance with the invention.

Figure 2 is a perspective view of the intermediate section of the hanger with the outer sections detached.

Figure 3 is a perspective view of one of the outer sections.

Figure 4 is a perspective view of the other outer section.

Figure 5 is a sectional view on the line 5—5 of Figure 1, being on an enlarged scale.

Figure 6 is a fragmentary longitudinal sectional view through the hanger.

Similar reference characters indicate corre-

sponding parts throughout the several views in the drawing.

Referring to the drawing in detail, the hanger constituting the present invention is denoted generally at A and involves intermediate and outer parts B and C, respectively, these being interfitted for adjustability, that is to say, the outer parts C interfit the intermediate part B.

The intermediate part B is made from sheet metal and comprises an elongated medial body portion 10 from opposite ends of which extend outwardly directed arms 11. The medial portion at opposite longer edges is turned outwardly and inwardly to provide guide flanges 12, which are coextensive with said medial portion 10 while removed slightly from a center point of the part B and into the arms 11 are horizontally aligned elongated slots 13. The outer ends of the arms 11 are provided with holes 14 for accommodating fasteners which are adapted to secure the hanger to the head of a window frame or casement to hold the hanger in a fixed, fast position.

The outer parts C are in the form of flat slideable arms 15 having at their outermost portions outturned wings or ears 16 and 17, respectively, which are at right angles to the said arms. The wing or ear 16 is formed with a notch 18 while the wing or ear 17 is provided with a hole 19, these being for the purpose of journaling a shade roller (not shown), which is conventional. The arms 15 are engaged between the flanges 12 of the part B to be in juxtaposition to the arms 11 thereof and are slidably adjusted outwardly or inwardly with relation to this part B.

Each arm 15 has provided therein holes 20 and the one adjacent to the innermost end of such arms accommodates a rivet 21, which is also engaged in the companion slot 13 therefor in the part B while adapted for engagement in any one of the remaining holes 20 is a nut-carrying fastener or bolt 22, being also engaged in the slot 13 companion thereto and through the use of the latter the parts C can be fastened in adjusted position with relation to the part B. Thus the hanger, by reason of the construction before described, can be assured to fit various widths of window frames or casements for the hanging of a window shade (not shown) thereby in proper position with respect to the window frame or casement.

The construction of the parts B and C affords a maximum range of adjustment for the extending of the hanger as well as the contracting thereof.

What is claimed is:

1. A hanger of the character described comprising intermediate and outer sectional parts, guide flanges in opposed relation to each other on the intermediate part and slidably accommodating the outer parts, elongated flat extensions on the main body of the intermediate part and forming a continuation thereof and having slots carried into the said intermediate part between the flanges thereof, wings on the outer parts, and means accommodated in the slots and engaged in the outer parts for slidably connecting the said parts together.

2. A hanger of the character described comprising intermediate and outer sectional parts, guide flanges in opposed relation to each other on the intermediate part and slidably accommodating the outer parts, elongated flat extensions on the main body of the intermediate part and forming a continuation thereof and having slots carried into the said intermediate part between

the flanges thereof, wings on the outer parts, means accommodated in the slots and engaged in the outer parts for slidably connecting the said parts together, and fasteners securing the outer and intermediate parts together and accommodated in said slots.

3. A hanger of the character described, comprising an intermediate section of an elongated form having inwardly turned flanges forming guides at the center portion spaced a considerable distance from the ends, outer sections sliding within the guides and extending parallel and abutting the flat portions of the intermediate portion and having laterally turned ends for supporting a curtain rod, the outer sections having a series of openings through which are adapted to pass securing means which in turn pass through slots in the intermediate section.
